UNITED STATES PATENT OFFICE.

ALFRED A. THRESHER, OF DAYTON, OHIO.

TELESCOPIC-RAMMER MOTOR.

No. 805,598.

Specification of Letters Patent.

Patented Nov. 28, 1905.

Application filed July 24, 1905. Serial No. 271,097.

To all whom it may concern:

Be it known that I, ALFRED A. THRESHER, of Dayton, in the county of Montgomery and State of Ohio, have invented a certain new 5 and useful Improvement in Telescopic-Rammer Motors; and I do hereby declare the following to be a full, clear, and exact description of the same, reference being had to the accompanying drawings, forming a part of 10 this specification, and to the letters of reference marked thereon.

This invention relates to motors for telescopic rammers, such as set forth in my contemporaneous application, Serial No. 218,867, 15 which application discloses but has no specific claim for the invention of the present application.

The object of the invention is to provide a compact self-contained structure, the working 20 parts of which while accessible are nevertheless protected against injury and dirt and are so disposed as to be out of the way of the gun crew.

The invention of the present application 25 consists in certain novel details of construction and combinations and arrangements of the electric-motor mechanism of the rammer.

Referring to the accompanying drawings, Figure 1 is a side elevation of a rammer embodying the present improvements, but with the telescopic sections omitted. Fig. 2 is a 30 vertical section showing the electric motor and drive-gear, but with the upper portion of the rammer frame and mechanism broken away. Fig. 3 is a top plan view of the rammer as shown in Fig. 1.

Like letters of reference in the several figures indicate same parts.

The rammer mechanism proper or the telescopic sections, together with the mechanism directly connected therewith for extending and retracting the same, is similar to that now well known and is substantially as described in my before-mentioned application 40 or in the patent to Fenton, No. 627,404, June 20, 1899, and illustration or description of the same is not necessary further than to say that they are power-driven from the shaft B. This shaft B, together with all the operating 45 parts and motor, is carried by a mount or frame A, adapted to be located permanently in rear and in line with the gun when the latter is in loading position. Shaft B carries at one end a large drive-gear B', journaled on but connected with the shaft through a friction-clutch C, held up to its work by a spring 50

C', thus permitting the rammer mechanism to come to rest when the resistance is excessive and preventing destruction of the parts due to momentum if sudden resistance is encountered. From the gear B' a chain or link belt D extends back to the small gear D', preferably located directly on the motor-shaft E.

The motor is an electric motor which is 60 self-contained and is located in the rammer-mount directly beneath the telescopic-section chamber and in such a position that its fields and armature are within the mount, while the ends of its shaft project at the sides. Said 65 motor embodies in its construction a center or field ring F with inwardly-projecting poles f, and an external flange F', together with in-closing heads G and G', having bearings for the armature-shaft E. The motor, preferably 70 those portions of the field-ring adjacent the flange F' and head G', is formed to fit openings in the opposite side wall of the rammer-mount, while the flange F' fits against one of the side walls, as shown clearly in Fig. 2. To 75 retain the motor in place, the flange F' is bolted to the face of one side of the mount by bolts I, and the head G' is secured by tie-pieces H, secured to the head and mount by bolts I'. The annular flange, it will be seen, 80 positions the motor and serves as an effective brace, and the construction is such that while the field-ring and one head are rigidly and firmly joined with the mount the opposite head is removable without taking down the 85 entire structure. The motor is of the enclosed type, and as the most convenient construction the removable head is dished outwardly for the accommodation of the commutator K, the shaft-bearing, &c., and said 90 head may be provided with a door or hand-hole L, through which access may be had to the interior of the motor without the necessity of removing the head itself.

It will be particularly noted that the motor 95 is especially designed to occupy a small space longitudinally of the shaft so as to fit within a comparatively narrow mount or frame, leaving no projections liable to obstruct free passage of the gun crew around 100 the mount and motor.

What I claim is—

1. A motor for telescopic rammers embodying heads, armature, armature-shaft journaled in the heads and a field-ring connecting the heads said ring being of substantially uniform section to enter the rammer- 110

mount and having an external flange near one end adapted to abut against one of the faces of the rammer-frame; substantially as described.

5 2. The combination with the mount, having openings in its side walls, of the electric motor formed with exterior configuration to fit each of said openings and means for securing the motor to the mount; substantially as 10 described.

3. A motor for telescopic rammers embodying a field-ring having an external flange extending around the same for attachment to the motor-support and a head of less 15 diameter than the flange whereby the said head may be passed through the opening in

the support to the wall of which the flange is to be attached; substantially as described.

4. A motor for telescopic rammers embodying a cylindrical field-ring having an external flange extending entirely around the same and heads secured to the ends of the ring, one of said heads being of less diameter than the flange whereby said head may be passed through an opening in the motor-support and through which the flange will not pass; substantially as described. 20 25

ALFRED A. THRESHER.
